(57) **CLAIM**

The ornamental design for a Bluetooth speaker, as shown and described.

DESCRIPTION

FIG. 1 is a front, right, top perspective view of a Bluetooth speaker, showing my design.

FIG. 2 is a rear, right, and top perspective view of the Bluetooth speaker in FIG. 1.

FIG. 3 is a front, right, and bottom perspective view of the Bluetooth speaker in FIG. 1.

FIG. 4 is a front view of the Bluetooth speaker in FIG. 1. FIG. 5 is a rear view of the Bluetooth speaker in FIG. 1. FIG. 6 is a left side view of the Bluetooth speaker in FIG. 1.

FIG. 7 is a right side view of the Bluetooth speaker in FIG. 1.

FIG. 8 is a top view of the Bluetooth speaker in FIG. 1. FIG. 9 is a bottom view of the Bluetooth speaker in FIG. 1; and,

FIG. 10 is a rear, right, and top perspective view of the Bluetooth speaker in FIG. 1, shown with the charging port cover in an open condition.

The broken lines shown in the drawings are included for the purpose of illustrating portions of the Bluetooth speaker that form no part of the claimed design.
